UNITED STATES PATENT OFFICE.

JOHN H. KELLOGG, OF BATTLE CREEK, MICHIGAN.

ABDOMINAL SUPPORT.

1,205,749.

Specification of Letters Patent. Patented Nov. 21, 1916.

Application filed April 17, 1916. Serial No. 91,777.

To all whom it may concern:

Be it known that I, JOHN H. KELLOGG, a citizen of the United States, residing at Battle Creek, county of Calhoun, State of Michigan, have invented certain new and useful Improvements in Abdominal Supports, of which the following is a specification.

This invention relates to improvements in 10 abdominal supports.

The main objects of this invention are: First, to provide an improved abdominal support adapted for the supporting of the lower abdominal muscles, which is effective 15 as a support and at the same time is comfortable for the wearer. Second, to provide an abdominal support having these advantages which can be readily shaped or adjusted to meet the requirements or conditions 20 of the wearer. Third, to provide an improved abdominal support having these advantages which is simple and economical in structure.

Further objects, and objects relating to 25 structural details, will definitely appear from the detailed description to follow.

I accomplish the objects of my invention by the devices and means described in the following specification.

30 The invention is clearly defined and pointed out in the claims.

A structure which is a preferred embodiment of my invention is clearly illustrated in the accompanying drawing, forming a part 35 of this specification, in which:

Figure I is a front perspective view of my improved abdominal support. Fig. II is a detail horizontal view on a line corresponding to line 2—2 of Fig. I. Fig. III is a detail view of the front end of one of the body attaching or support members, showing the longitudinal twist in the blade spring member. Fig. IV is a front perspective view of the pad of the support illustrating the possible torsional or twisting movement between the parts or halves of the pad. Fig. V is a detail section showing the relation of the attaching stud to the pad members and of the support to the stud. Fig. VI 40 is a plan view of the outer back casing member. Fig. VII is a plan view of one of the plates. Fig. VIII is a detail rear view showing the manner of attaching the body pads to the rear ends of the support members.

In the drawing similar reference characters refer to similar parts throughout the several views, and the sectional views are taken looking in the direction of the little arrows at the ends of the section lines.

Referring to the drawing, the body of my improved abdominal support comprises a pair of plates 1, preferably formed of bendable metal, that is, metal which will permit bending of the plates within the pad so as to conform them to the requirements of the 60 wearer. These plates 1 are supported in a spaced relation by the casing back members 2 and 3 formed of leather, these casing members being of the shape and size of the pad. The plates are supported in their desired 65 relative positions within the pad by rows of stitching 4 around the edges of the plates. The back members form a hinge or flexible connection between the plates so that they may adjust themselves or may be adjusted 70 relative to each other. The plates are also preferably spaced a substantial distance apart so as to permit a relative twisting or torsional movement between them. The back members have a dart 5 extending from 75 their upper edge downwardly between the plates, the dart being formed by cutting out portions of the back members at 6 and stitching the edges together. This gives an inwardly dished shape to the upper portion of 80 the pad.

The plates 1 are oval in shape and disposed with their small ends downwardly. The front casing member 7 and the edges of the back casing members are stitched together by the row of stitches 8. A suitable filling 9 is disposed within the casing. With the parts thus arranged the pad may be flexed between the plates both on the vertical line and in a twisting or torsional manner.

The support members, designated generally by the numerals 10, comprise the curved blade springs 11 having key-hole slots 12 at their front ends adapted to be engaged with 100 the studs 13 mounted centrally on the plates 1 and projecting through the rear casing back member 2, which is provided with holes 14 to receive the same.

The spring members 11 are provided with 105 a leather or other suitable covering 15 and have body engaging pads 16 at their rear ends, the pads being adapted to rest against

the back of the wearer. These pads are adjustably secured to the members 11 by the screws 17, the members 11 having a series of holes 18 adapted to receive the screws. The 5 front ends 19 of the members 11 are given a longitudinal twist so that they engage the studs as shown in Fig. V, the upper edges of the slots 12 engaging the upper sides of the studs and the lower edges of the springs 10 bearing against the pad. This supports the pad with an upwardly and inwardly twisting action, the object being to secure an inward and upward pressure on the lower end of the pad as well as the general inward 15 pressure of the pad.

My improved abdominal supporter is very efficient for the purpose for which it is intended and is comfortable in that it tends to adjust itself to the movements of the wearer 20 and, at the same time, effectively performs its functions as a support. Further, the plates may be conformed to meet the particular requirements or conditions.

Having thus described my invention, what 25 I claim as new and desire to secure by Letters Patent, is:

1. In an abdominal supporter, the combination of a pad comprising a pair of oval plates of metal bendable to permit conforming within the pad, a pair of casing back members between which said plates are disposed in a spaced relation with their small ends downward, said back members being stitched together around the edges of the 35 plates, there being a dart extending from the upper edge of said back members centrally between said plates providing an inward dish to the upper edge of the pad, said back members constituting a flexible connection 40 between said plates, said plates being spaced to permit limited relative torsional movement between the halves of the pad, a front casing member stitched at its edges to the edges of said back members, there being a 45 filling between said front and back members, studs mounted centrally of said plates, and body attaching members comprising curved blade springs provided with pads at their rear ends adapted to rest against the back of 50 the wearer and having key hole slots at their front ends adapted to engage said studs, said springs being twisted at their front ends so that they engage the studs with an inward and upward twisting action.

55 2. In an abdominal supporter, the combination of a pad comprising a pair of oval plates, a pair of casing back members between which said plates are disposed in a spaced relation with their small ends downward, said back members being stitched together around the edges of the plates, said back members constituting flexible connection between said plates, said plates being spaced to permit limited relative torsional

movement between the halves of the pad, a 65 front casing member stitched at its edges to the edges of said back members, there being a filling between said front and back members, studs mounted centrally of said plates, and body attaching members comprising curved blade springs provided with pads at their rear ends adapted to rest against the back of the wearer and having key hole slots at their front ends adapted to engage said studs, said springs being twisted at 70 their front ends so that they engage the studs with an inward and upward twisting action.

3. In an abdominal supporter, the combination of a pad comprising a pair of oval 80 plates of metal bendable to permit conforming within the pad, a pair of casing back members between which said plates are disposed in a spaced relation with their small ends downward, said back members being 85 stitched together around the edges of the plates, there being a dart extending from the upper edge of said back members centrally between said plates providing an inward dish to the upper edge of the pad, said back 90 members constituting a hinge connection between said plates, said plates being spaced to permit limited relative torsional movement between the halves of the pad, a front casing member stitched at its edges to the 95 edges of said back members, there being a filling between said front and back members, and curved resilient body attaching members connected centrally to said plates.

4. In an abdominal supporter, the combination of a pad comprising a pair of oval plates, a pair of casing back members between which said plates are disposed in a spaced relation with their small ends downward, said back members being stitched together around the edges of the plates, said back members constituting a hinge connection between said plates, said plates being substantially spaced permitting torsional flexing of the back members between the 110 plates and thereby providing for relative torsional movement between the halves of the pad, a front casing member stitched at its edges to the edges of said back members, there being a filling between said front and 115 back members, and curved resilient body attaching members connected centrally to said plates.

5. In an abdominal supporter, the combination of a pad comprising a pair of plates, 120 a pair of casing back members between which said plates are disposed in a spaced relation, said back members being stitched together around the edges of the plates, said back members constituting a flexible connection between said plates, a front casing member stitched at its edges to the edges of said back members, there being a filling between 125

said front and back members, studs mounted centrally of said plates, and body attaching members comprising curved blade springs provided with pads at their rear ends adapted to rest against the back of the wearer and having key hole slots at their front ends adapted to engage said studs, said springs being twisted at their front ends so that they

engage the studs with an inward and upward twisting action.

10

In witness whereof, I have hereunto set my hand and seal in the presence of a witness.

JOHN H. KELLOGG. [L.S.]

Witness:

ROY TUTTLE.
